UNITED STATES PATENT OFFICE.

STENCHEL FILIPEK, OF WESTVIEW, OHIO.

WINDOW FIXTURE.

Application filed May 11, 1920. Serial No. 380,628.

To all whom it may concern:

Be it known that I, STENCHEL FILIPEK, a citizen of the United States, residing at Westview, in the county of Cuyahoga and State of Ohio, have invented new and useful Improvements in Window Fixtures, of which the following is a specification.

This invention relates to a shade and curtain support, the principal object of the invention being to provide a pair of brackets for supporting both the curtain pole and shade roller with means for adjusting the roller supporting means to make the device fit rollers of varying lengths.

Another object of the invention is to provide means for positively holding the pole in place on the bracket.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view showing the invention applied to a window.

Figure 2 is an end view of a part shown in Figure 1.

Figure 3 is an enlarged view of one of the brackets.

Figure 4 is a vertical section through Figure 3.

Figure 5 is a detail view of the means for holding the pole in position.

Figure 6 is a perspective fragmentary view of a portion of one of the brackets and illustrates the channel providing the guide means for the shade roller holder.

In these drawings 1 indicates the window casing, 2 the curtain pole and 3 the shade roller. The pole and roller are supported by a pair of brackets 4, each bracket consisting of an angle part 5 provided with openings for permitting it to be screwed to

the casing. The vertical limb of said part having a forward extension 6 extending at right-angles from its upper end and pro-

vided with a curved extremity 7 to receive the curtain pole. The holder member of the angle part has its edges bent to form the channel as at 8 to provide a guide for the shade roller holder 9. This holder is of angle shape with the limb engaging the channel provided with an elongated slot 10 through which the bolt 11 passes which secures the holder in the channel. The curtain pole is held in the curved extremity of the extension 6 by the hinged latch 12 having its ends engaging openings 13 in said extension.

It will thus be seen that after the brackets are secured to the window casing the holders for the shade roller can be adjusted to suit rollers of various lengths and that the curtain pole is held in spaced relation to the roller and is secured in position by the latch member.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A window fixture of the character described comprising an angle bracket including a horizontal part for supporting the bracket and having its upper and lower edges bent to form a channel, a vertical limb forming a continuation of a portion of the upper side edge and rising from one end of the horizontal part, a forward extension arranged at right angles from the upper end of the vertical limb and being provided with a curved extremity to receive a curtain pole, a reduced portion terminating from the curved extremity and being rounded upon itself, a latch pivotally carried by the reduced portion and having its free ends received in spaced openings formed in the forward extension, and an angle shaped shade roller holder adjustably secured in the channel of the horizontal part.

In testimony whereof I affix my signature.

STENCHEL FILIPEK.
